UNITED STATES PATENT OFFICE

HENRY G. ROTH, OF MINNEAPOLIS, MINNESOTA.

DETACHABLE BOX-COVER.

No. 801,402.

Specification of Letters Patent.

Patented Oct. 10, 1905.

Application filed February 6, 1905. Serial No. 244,302.

To all whom it may concern:

Be it known that I, HENRY G. ROTH, a citizen of the United States, residing at Minneapolis, in the county of Hennepin and State 5 Minnesota, have invented certain new and useful Improvements in Detachable Box-Covers; and I do hereby declare the following to be a full, clear, and exact description of the invention, such as will enable others skilled in the 10 art to which it appertains to make and use the same.

My present invention has for its especial object to provide an improved detachable cover for cracker-boxes and boxes of a similar character; and to such ends it consists of the novel devices and combinations of devices hereinafter described, and defined in the claims.

As is well known, crackers, cookies, and certain other groceries and certain classes of confectionery are sold out of boxes in which they are put up and shipped, and to afford ready access thereto and at the same time to protect the goods detachable covers, usually having hinged sections, have been applied to close the 25 open sides of such boxes. Various devices have been provided for securing these detachable covers to the boxes. One feature of my invention is directed to improved means for detachably securing these covers to the boxes, 30 and another feature of my invention is directed to a novel arrangement of the cover with respect to the box and of internal partitions, which adapt the box to be turned first one side and then the other side up, so that 35 the goods may all be sold from the uppermost section of the box. This feature of construction is very desirable, because purchasers usually object to receiving what they consider the leavings at the bottom of the box, which 40 in the case of such articles as crackers and cookies are liable to be more or less broken.

The invention also comprises other novel features of construction, as will hereinafter appear.

45 In the accompanying drawings, which illustrate my invention, like characters indicate like parts throughout the several views.

Figure 1 is a plan view showing a box having applied thereto a detachable cover or side 50 embodying the several features of my invention. Fig. 2 is a front elevation of the parts shown in Fig. 1. Fig. 3 is a section on the line $x^3 x^3$ of Fig. 2, showing also by dotted lines a portion of a second box set upon the 55 box indicated by full lines. Figs. 4 and 5 are detail views, on an enlarged scale, taken in

section on the line $x^4 x^5$ of Fig. 3. Fig. 6 is a section on the line $x^6 x^6$ of Fig. 4. Fig. 7 is a front elevation of the upper portion of the detachable cover with the hinged section thereof turned downward. Fig. 8 is a front elevation of the cover with its hinged section turned downward and with some parts broken away. Fig. 9 is a horizontal section on the line $x^9 x^9$ of Fig. 3, some parts being broken away; and 65 Fig. 10 is a vertical section on the line $x^{10} x^{10}$ of Fig. 7.

The numeral 1 indicates a rectangular box, such as a cracker-box, shown as set with its open side in a vertical position. This box is 70 divided into upper and lower compartments by a horizontal partition 2, detachably fitted in grooves formed in the end plates of the box.

The detachable cover is preferably, but not necessarily, of the form set forth and broadly 75 claimed in my United States Letters Patent No. 737,776, of September 1, 1903, entitled "Detachable cover for boxes," and it comprises triangular end plates 3 and inclined outwardly-bulging side plates 4 and 5. The lower 80 section 4 is rigidly, but detachably, secured to the end plates 3, preferably by screws 6. The upper section 5 affords a lid, which is pivotally connected to the lower section 4 by hinges 7 and, as shown, is provided at its upper edge 85 with a finger-piece 8. The sections 4 and 5 are preferably provided with glass panes 4^a and 5^a, respectively, so that the goods may be viewed therethrough.

A thin joint-strip 9, preferably of sheet 90 metal, having an outturned flange 10, is adjustably secured to the upper ends of the end pieces 3 by screws 11, that work through vertically-elongated slots 12 in said strips. The slots 12 are provided with lateral enlargements 12^a, through which the heads of the screws 11 may be passed in the application or removal of said joint-strip. The panes 4^a and 5^a at their abutting edges are seated in split 95 metallic tubes 13, the ends of which are flattened and rigidly secured to the sides of the respective sections 4 and 5 and afford braces 100 which tie together the said sides.

The angular side pieces 3 of the detachable cover on their vertical edges and near the central portion of the cover are notched at 3^a to afford seats for a pair of grapples 14, the members of which, as shown, are loosely pivoted to hinge-clips 15, rigidly secured to said side pieces within said notches 3^a. The free ends 105 of the grapple members 14 are formed with 110 opposing teeth 14^a. Small bolts 16 are passed

through the grapple members and at one end, preferably their inner ends, are provided with thumb-nuts 17. Coiled springs 18, placed on the bolts 16 between the grapple members, 5 tend to open the said members up as far as permitted by the nuts 17. The toothed free ends of the grapple members project beyond the side plates 3, so that they are adapted to engage the adjacent edges of the end plates 10 of the box 1.

On their inner faces close to their vertical edges the end plates 3 are formed with vertical grooves 3^b, in which works slidably a vertical partition-board 19. (See particularly 15 Figs. 3 and 9.) This partition-board 19 in vertical dimensions equals, approximately, one-half the height of the box 1 when the latter is set, as shown in Fig. 3, and it is normally adjusted, as shown in said Fig. 3, so that it 20 closes the lower compartment of said box.

Preferably one or more display tags or cards 20 are suspended from the central portion of the joint-strip 9 in position where they may be seen through the glass pane 5^a when the 25 lid 5 is closed and through the opening afforded when the said lid is opened. Upon these cards or tags the price, the name, trade-mark, or other advertising matter pertaining to the contents of the box may be marked.

30 Fig. 3 best shows the adjustments of the parts with the detachable cover applied to the box. The grapples 14 are capable of considerable lateral adjustment, so that they will catch onto the end plates of the box even when 35 the box is considerably wider or considerably narrower than the cover. This adjustment is made clear by reference to Figs. 4 and 5. The joint-strip 9 by vertical adjustments adapts the cover for application to boxes that vary 40 considerably in height, as clearly indicated by full and dotted lines in Fig. 3. These adjustments adapt the cover for application to boxes that vary considerably in size and for commercial use, where the boxes vary considerably 45 in dimensions, are an important feature.

With the parts adjusted as shown in Fig. 3 both compartments of the box may be assumed to contain crackers or other articles, some of which are also placed in the angular 50 compartment afforded by the lower portion of the cover between the vertical partition 19 and the lower side or plate section 4. These articles placed in this lower compartment of the cover may be nicely arranged for display 55 purposes and need not be disturbed in selling the goods from the box. The lower compartment of the box is closed by the partitions 2 and 19, and a purchaser cannot tell whether or not this compartment contains the goods. 60 Apparently the box will be full, or at least filled to a point above the partition 2. When the upper compartment of the box has been nearly or quite emptied, the cover should be removed, the box turned upside down, and 65 the cover then again applied. After this is

done the crackers or other articles contained in the filled upper compartment may be sold out until the box is emptied.

The detachable cover above described is of course intended to be used indefinitely over 70 and over again with different boxes in which the articles to be sold are shipped to the retailer. The cover itself may be easily knocked down, so that the parts may be packed flatwise in very small space. To do this, it is 75 only necessary to remove the screws 6, thereby detaching the sections 4 and 5, and then the joint-strip 9 may be removed, thereby separating and disconnecting the end plates 3. The hinged sections 4 and 5 may of course 80 be turned flatwise together for the purposes of packing. The partition 19 when the end plates 3 are disconnected falls from working position. By shipping the parts of the cover closely packed, as is above made possible, a 85 great saving is effected in freight rates.

It will of course be understood that the box and the cover are capable of use in various positions. In fact, I contemplate their use on top of a counter with the open side of the 90 box turned upward and with the cover applied thereto. When thus applied to an ordinary counter, it has the appearance of an ornamental show-case and has the advantages already set forth in connection with the description of the box set on its edge with the cover closing the vertical side thereof.

It will of course be understood from what has been said that the device described is capable of modification within the scope of my invention, as herein set forth and claimed.

It will be understood that in some instances both of the plates 4 and 5 of the detachable cover might be hinged, in which case suitable latches would usually be provided therefor. 105 The sliding partition 19 is capable of movement in the grooves 3^b into positions in which it will close at will either compartment of the box.

What I claim, and desire to secure by Letters Patent of the United States, is as follows:

1. The combination with a box, of a detachable cover provided with means for securing it to an open side of said box, said detachable cover having outwardly-converging 115 side plates, one of which, affords a lid, and a vertical inner plate or partition extending approximately to the center of said cover and coöperating with the lower or converging side plates of said cover, to afford an upwardly-diverging pocket, substantially as described.

2. A detachable box-cover having triangular end plates, outwardly-converging side plates, one of which affords a lid, and a vertical inner plate or partition, the latter extending approximately to the central portion of said cover and coöperating with the lower, converging plate thereof, to form an upwardly-diverging pocket, substantially as described.

3. The combination with a box having an 130

outwardly-bulged side section, provided with a lid, of a partition dividing the body of the box into compartments, and a partition separating one compartment of the box from a portion of the compartment formed within said bulged portion, substantially as described.

4. The combination with a box having a partition dividing it into two compartments, and having an outwardly-bulged extension, of a movable partition adapted to be moved from one position to another, to close either compartment of said box from the compartment of said bulged portion, substantially as described.

15 5. The combination with a box having a partition dividing it into two compartments, of a detachable cover therefor formed with triangular end plates, outwardly-converging walls, at least one of which is hinged, and a sliding partition movable to close either compartment of said box from the compartment of said cover, substantially as described.

6. The combination with a box and a detachable cover, of coöperating grapples applied to and working in notches formed in one 25 of the said members, and engageable with the other of said members, in different angular positions, substantially as described.

7. The combination with a box and a detachable cover, arranged to increase the capacity of the box, pivotal grapples working in the notches formed in the sides of said cover, and having at their free ends jaws engageable with the sides of said box in different angular positions, and means for clamping the jaws of 35 said grapples onto the sides of said box, substantially as described.

In testimony whereof I affix my signature in presence of two witnesses.

HENRY G. ROTH.
